AUTOMATIC BALANCING SYSTEM FOR
CLEANING MACHINE CYLINDERSLeo M. Kahn and Edwin Ellner, New York, N. Y.;
said Ellner assignor to said Kahn

Application May 26, 1948, Serial No. 29 376

43 Claims. (Cl. 74—573)

1

This invention relates to damp drying systems for laundered or otherwise cleaned articles wherein the extraction of the washing or other cleaning fluid from the articles is effected through high speed rotation of a cylinder which is perforated or otherwise provided with fluid extraction and discharge means.

It is well understood that the degree of drying of articles in machines of the above nature depends upon the extent of the centrifugal force produced by high speed rotation of the cylinder so as to eject the fluid from the articles. However, articles of wet clothing, from their very nature, are generally unsymmetrically distributed in the cylinder, particularly when the cylinder rotates about a horizontal axis, and such undesirable weight distribution produces severe vibrations in the rotating cylinder which impose a limit upon the speed of rotation and adversely affect the degree and time of drying in addition to being potentially injurious to the machine. In practice, most cleaning establishments have found it necessary to divide a cylinder into radial chambers by using partitions and weighing the articles put into each chamber in order to secure initial balance prior to high speed rotation. It is evident that such a practice is time consuming and laborious and furthermore does not anticipate changes in weight distribution as the extraction of fluid proceeds to completion. Many establishments which dispense with such precautions are required to be on substantially constant guard to avoid excessive vibration and consequent danger.

In the forms shown herein, a cylinder is provided with peripherally disposed pockets to which are selectively and automatically applied, by electrical controls, counterbalancing fluids in such a manner as to neutralize the effect of improper weight distribution within the cylinder. Accordingly, the instant application has as an object thereof, means to establish or identify the portion of the cylinder in which an overweight occurs and the automatic disposition of fluid material to neutralize such overweight and secure a satisfactory rotating or running balance as the extracting process continues to completion, the apparatus being further designed to continue the application or other disposition of counterbalance fluid in respect to an indicated pocket notwithstanding continued rotation of the cylinder. Such continuity of application embodies many advantages such as will be set forth hereinafter.

Another object of this invention is to provide a series of angularly spaced peripheral pockets on

5 a cleaning machine cylinder or extractor, and including rotating fluid feeding rings, each of the rings being arranged to feed fluid to the respective pockets and being so formed as to concentrate fluid injected therein into a position where it may be most effectively piped to the pockets. In this connection, advantage is taken of the rotation of the cylinder and the ensuing generation of centrifugal forces to direct the counterbalance fluid into a specific site for piping it to the pockets, as above described. The pockets are further formed as to effectively retain fluid during the extraction period and to automatically and inherently discharge it when the speed of rotation decreases sufficiently.

10 Another object of this invention is to provide a washing machine or other type of cleaning apparatus wherein counterbalancing fluid is electrically directed to peripherally disposed chambers or pockets of a horizontal cylinder as required by a specific state of unbalance, the apparatus being designed to effectively feed a plurality of revolving pockets or chambers simultaneously if required to secure the running balance, the apparatus being further arranged to automatically dump or eject the counterbalance fluid when any one 15 cycle of operations has been completed and without interfering with the normal cleaning and damp drying functions of the machine.

20 Still another object of this invention is to provide a horizontally rotating cylinder of elongated form wherein the balancing apparatus of the above general description is applied to both ends of the cylinder independently so that the counterbalancing operations may serve both the static and dynamic balance conditions of the rotating cylinder.

25 30 35 40 45 50 A further object of this invention is to provide an electrical pick-up device of either the self-generating or switch type as hereinafter disclosed, for establishing the existence of a state of unbalance in a rotating cylinder by determining the vibration thereof, the device being mounted on the apparatus or on the cylinder itself and being responsive to variations of vibration forces along the cylinder or shaft thereof instead of to vibrations of the apparatus relative to its floor or like support. It has been found that such disposition is highly effective in that it is less sensitive to extraneous shock or stimulation.

55 Other and most important objects of this invention include the provision of a simple electrical circuit for achieving all of the foregoing objectives, the provision of means for avoiding undue wear on valves, relays and the like, and the re-

quired accomplishment of a state of balance before the machine enters into its highest speeds of operation.

The invention is generally applicable to household or commercial washing or extracting machines as well as dry cleaning machines or the like. Whereas washing machines employ water as the cleaning medium, such dry cleaning machines generally employ organic solvents which are usually volatile.

Other objects of my invention will become apparent from the following description of the disclosed form of the invention.

Referring to the drawings:

Fig. 1 is a side view, partly broken away, of one form of the apparatus of the instant invention.

Fig. 2 is a cross-sectional view along the lines 2—2 of Fig. 1 and including a conventional type of electrical vibration pick-up device.

Fig. 3 is a fragmentary front view of three balancing control valves and piping therefor.

Fig. 4 is a schematic diagram of the electrical or electronic circuit.

Fig. 5 is a schematic diagram of the motor control circuit as used in conjunction with the circuit of Fig. 4.

Fig. 5A shows a slight modification of that portion of the motor control circuit that includes the master control valve.

Fig. 8 is a cross-section view along the lines 8—8 of Fig. 7.

Fig. 9 is a fragmentary view of a modification of the fluid feeding system disclosed in Fig. 7.

Fig. 10 is a top fragmentary view of a pick-up device which is of particular utility in connection with the foregoing balancing apparatus.

Fig. 11 is a side elevational view of the device of Fig. 10.

Fig. 12 is a view similar to Fig. 1 but illustrating a modified form of fluid piping system as well as a modified form of pick-up device.

Fig. 13 is a view along the lines 13—13 of Fig. 12.

Fig. 14 is a modified embodiment of the electrical circuit, such modified embodiment eliminating the electronic tube elements of Fig. 4.

Fig. 15 is a schematic view of a modification of the hold-over circuit.

Fig. 16 is a view similar to Fig. 1 but illustrating a composite apparatus particularly useful for dry-cleaning systems employing organic fluid solvents or the like such as are commercially used in the dry-cleaning industry, and including a modification in the fluid feeding system.

Referring to Fig. 1, the apparatus in the form shown, includes a cylinder 17 wherein wet clothes or other articles may be damp dried through centrifugal extraction. The cylinder or drum 17 is supported or driven at one end thereof, the embodiment here shown being generally referred to as a rigid bearing, single end supported machine. This is to be distinguished from a yieldable bearing for permitting free cylinder oscillation. Driving power for the cylinder originates in electric motor 18 which may be driven at a low speed for tumbling of the articles in the cylinder and at a high speed for the centrifugal

extraction of fluid from the cleaned articles. This sequence of actions is that which obtains when the machine is either a complete laundry or dry cleaning apparatus. If the apparatus is used for extraction alone, as is well known, the two speeds of operation may be modified depending upon the particular type of machine. The pulleys and belts illustrated may serve to transmit the driving power to the main shaft 19 so that the cylinder is rotated pursuant to the controlled speed of motor 18. As is well known in the laundry or dry cleaning type of apparatus, the various operations may be electrically controlled through a time cycle mechanism wherein the application of water or other cleaning fluid, and the commencement of tumbling or cleaning speed rotation, rinsing, extraction, etc., are automatically performed. Such mechanism being common and well understood in the art, is not here illustrated. Briefly, the cycle generally commences by introducing water or other cleaning fluid into the stationary shell or tub which contains the rotatable cylinder 17. A water level control may serve to fill the shell about one-third of its height whereupon the washing or tumbling operation may commence, detergent or other cleaning substance having first been applied.

In the machines having vertical cylinders, the tumbling means will take some other form, as for example, an agitator or the like. At the conclusion of the washing operation, a dump valve in the shell is opened and the dirty wash water released, whereupon the dump valve may be closed and a rinsing operation may follow. Following this, the dump valve is again opened, the rotation speed of the cylinder is greatly increased, and the centrifugal extraction operation commences. The cylinder may either be perforated or may have some other conventional means to discharge or receive the washing fluid.

In laundry systems the fluid is dumped as waste but for so-called dry cleaning systems, the organic cleaning fluid, with or without a soap ingredient, is filtered, and re-used. As an extactor, substantially only the higher speeds may generally be used. In conjunction with the invention disclosed, we contemplate the use of a balancing system effectuated through counterbalance fluid of the same nature as that employed for the cleaning operation so that they may mix and share common paths of flow. In general, the balancing system disclosed offers the practical realization of extremely high speeds of cylinder rotation permitting, for example, a horizontal cylinder to damp-dry at new orders of effectiveness while being available as a horizontal washer. This combination of functions has been long desired by the industry.

Cylinder 20 is arranged to receive, wash and damp-dry clothes in the interior thereof and ribs 21, 22 and 23 may be provided to assist in the washing function. According to the herein illustrated embodiment of the instant invention, the ribs are made hollow with solid or enclosed rear end walls and are also employed as pockets or chamber elements for receiving weight counterbalance fluid as will be hereinafter described, although it will be evident that they may serve purely as fluid receiving pockets without participating in the washing function. The pockets are angularly and equally spaced around the periphery of the cylinder so as to effectively divide it into three weight receiving portions 120

degrees apart although it is evident that four or even more ribs or pockets may be employed and spaced apart accordingly.

It is further evident that the pockets may be formed on the outside, rather than the inside of the cylinder, and, if desired, conventional inside ribs may be used for the agitating or clothes lifting function. Such an expedient is illustrated in our prior application, Serial No. 673,680, filed May 31, 1946, and in such case the washing ribs may be perforated or the like as is well known, such rib construction being often considered of advantage for washing purposes.

Means are provided to feed water or other counterbalance fluid from a tank 25 to the pockets when required by a condition of unbalance. Electrically controlled feed valves 26, 27 and 28 are provided for this purpose, the operation and control of which will be hereinafter described, although each of the feed valves may be replaced by individual and similarly controlled fluid pumps. Assuming that the valves are actuated as required, the fluid flows through the feed pipes 29, 30 and 31 and to the upwardly operating jets 32, 33 and 34. It will be understood that either one or two of such feed pipes will operate at any one time in order to correct a condition of unbalance.

Assuming now that valve 26 has caused the fluid to flow through pipe 29, such fluid will flow through jet or nozzle 32 and into the feed ring 35. Feed ring 35 is arranged to feed the fluid through pipe 36 into pocket 21, while feed rings 31 and 38 are arranged to feed pockets 22 and 23 respectively through the pipes 39 and 40 respectively.

The feed rings are channel or U-shaped in cross-section and are open along their entire annular floors so as to have an endless inlet. The feed rings together may form a unitary sub-assembly as by being welded together in the relationship illustrated. Such sub-assembly is made fast to the cylinder so as to rotate therewith, by tack welding, or otherwise securing the side wall 41 of feed ring 38 to radiating ribs 42 which are themselves secured to cylinder end wall 43. The feed rings are disposed about hub 44 of shaft 19 and each in angularly spaced eccentric relation thereto for purposes which will hereinafter be made clear although it is to be understood that such disposition is not essential, as will be described.

When, for example, fluid is applied through jet 32 to the open annular floor of feed ring 35, centrifugal force will direct and maintain such fluid adjacent the periphery of the feed ring notwithstanding the fact that each feed ring is open at its center and annular floor. As jet 32 injects the fluid into feed ring 35 during rotation of the cylinder, such fluid is forced through pipe 36 and into the upper portion of pocket 21 which is closed by end wall 45, the bottom of the pocket being open at 46, thus serving as a discharge outlet for the pocket as will hereinafter appear.

The feed rings are shaped and connected so as to rotate eccentrically with respect to shaft 19 and are formed with discharge openings 35a at the furthest point of eccentricity. Such disposition insures that the opening 35a is always at the furthest distance from the shaft relative to any other point within feed ring 35. Accordingly, when fluid is injected into the open channel of feed ring 35, centrifugal forces generated by the rotation of feed ring 35, cause

the fluid to collect adjacent opening 35a so as to be more effectively fed or forced through pipe 36. In fact, such force is generally sufficient to impel the fluid a considerable distance so that the expedient of directing the furthest point of a feed ring toward its associated pocket may be desirable but not necessary.

It will be evident that jets 32, 33 and 34 do not rotate but extend into the shell from the stationary pipe 29 to 31 which traverse opening 47a of shell 50a. Fluid flowing from the jets will be collected in any position of the rotating feed rings and such fluid collected by the rings will be directed toward the respective outlets. Feed rings 31 and 38 are likewise eccentrically disposed and their eccentricities may be angularly spaced 120 degrees apart from each other to correspond to the pocket disposition. The provision of the feed rings, shaped and disposed to take advantage of centrifugal forces, makes possible a faster and more positive distribution of the counterbalance fluid so as to achieve such distribution in short order and to keep pace with the changing weight distribution as the fluid is extracted from the articles. It has been determined that in the absence of employment of positive force, the injected fluid tends to spread along the inner periphery of the rings and the accomplishment of balance is greatly and perhaps intolerably delayed because the fluid feeds too slowly to the weight receiving elements or pockets.

As pocket 21 fills with fluid introduced through pipe 36, such fluid is maintained along the inner peripheral surface of the pocket pursuant to centrifugal force. The fluid may accumulate as far down as the lower edge of end wall 45 whereupon it will enter the stationary shell or tub 47 through opening 46 of the pocket 21. However, the pockets will be of such size as to accommodate any conceivable degree of unbalance within the intended operation of the machine as hereinafter set for h. Accordingly, the injected counterbalance fluid will be retained by wall 45 during the extraction operation. At the termination of such operation, and when the speed of cylinder rotation decreases sufficiently, the counterbalance fluid will rapidly discharge outside of the cylinder through opening 46 in preparation for a succeeding operation. It can be seen, therefore, that by relying on centrifugal forces to maintain the fluid as injected, the discharge may be facilitated and its required duration materially decreased. It will further be observed that the floor 46a of the pocket 21 is inclined toward the discharge opening 46 so as to more effectively discharge the fluid therethrough.

Each pocket thus discharges its fluid as the cylinder slows down to a tumbling speed. The fluid then enters the shell 50a which may include the apron 47 and it discharges through the outlet pipe 48, through valve 49, into the used fluid tank 50 or other outlet depending upon the character of the machine.

The disposition of the discharge outlet 46 at the lower portion of the pocket is of further importance in clearing the general water level in the shell or cylinder during extraction. During a tumbling process any fluid picked up by the pockets will be discharged practically at once. Cleaning fluid is thrown toward the wall of the shell from which it is drained so that it does not tend to enter the discharge outlet 46. During discharge from the pockets the counterbalance

fluid is isolated from the damp-dried articles by the solid end wall 43 in back of which the fluid discharges. The pockets may discharge the counterbalance fluid into the shell by having their floors inclined as disclosed in our previous application. It may further be noted that the fluid instead of being fed through the pipes 29-31 as in the preferred embodiment, may be fed through the rotating trunnion of shaft in the manner disclosed in such previous application. Thus, the fluid may be directly applied to the pockets through bores in the trunnion as in the previous application or it may be transferred from such bores to the feed rings disclosed herein prior to its injection into the pockets.

In the embodiment illustrated, the machine takes the general form of a dry cleaning apparatus, although a washing machine will operate identically. If the cylinder is vertical instead of being horizontal as shown, the balancing pockets will also be vertical, as will be obvious or may be horizontally arranged around the base of the cylinder or basket as will be understood from the elongated horizontal cylinder hereinafter disclosed. As a dry cleaning apparatus, the used fluid tank 50 receives both the contaminated cleaning fluid as well as the counterbalancing fluid and feeds such combined fluids, usually after filtering, into tank 51 through pipe 52. Further details of such a system are described in connection with Fig. 16. The filtered or clean fluid is then utilized for further cleaning and counterbalancing operations. As a washing machine, it is evident that water will generally be used for this purpose although any fluid may be employed including mercury, preferably maintaining it isolated from the cleaning fluid.

Pump 53 serves to bring the counterbalancing fluid from tank 51 up through master valve 54, through pipe 55, to the three solenoid feed valves 26, 27 and 28, wherefrom it may proceed to the jets 32-34 pursuant to the controlled action of the feed valves, as hereinafter set forth. The provision of master valve 54, operated in one manner as will appear hereinafter, is thought to be desirable in that it adds an additional precaution against fluid leaking and travelling into pockets apart from the action of the control system. The use of a pump is considered to be of some advantage since it predetermines the fluid feeding pressure and avoids random rates of fluid flow.

The physical elements of the apparatus, excluding the foregoing details of the counterbalancing system, are generally conventional. Thus, the shell 58a may be provided with hinged door 56 to deposit or remove the articles from the cylinder. Shaft 19, being shown as somewhat elongated, may be maintained in two spaced anti-friction bearings 57 and 58 which may themselves be suitably supported as desired. The motor 18 is either a two-speed motor or one of variable speed, a lower speed being used for tumbling of the articles as during cleaning *per se*, while a considerably higher speed is used for the centrifugal extraction operation. If the machine takes the form of an extractor without washing features, such lower speeds may be used for predisposition functions in achieving a rough balance prior to the action of the corrective system disclosed.

The electrical operation comprising the control system of the apparatus will now be described. The apparatus applies counterbalancing

7 fluid to selected pockets during acceleration and high speed rotation of the cylinder and in response to a specific condition of unbalance. Means are provided to establish the presence of a predetermined degree of unbalance and its location, and certain corrective measures are thereupon automatically put into effect. Means synchronized with the rotation of the cylinder are utilized to provide a reference voltage by which the instantaneous position of a particular segment of the cylinder may be momentarily established. Thus, the site of unbalance can be located, the presence and degree of which is indicated by a vibration-responsive device, as hereinafter described.

8 An electrical circuit is provided which reacts to joint stimuli, one of which is the reference voltage and instantaneously establishes the position of successive pockets of the rotating cylinder while the other simultaneously provides an indication of the presence as well as the degree of unbalance. Jointly, they produce a reaction in the circuit which is so timed by the reference voltage that the site of required correction is thereby established. Such reaction is arranged to energize one or more solenoids so as to open one or more associated valves 26, 27 and 28 and thereby introduce counterbalance fluid into selected feed rings and pockets.

30 In order that the explanation of the electrical circuit be more comprehensible in relation to the operation of the apparatus, the following principles of operation may be noted.

When the overweighted portion of the unbalanced, rotating cylinder passes a predetermined point, the actuating portion of an electrical signal is produced. This signal indicates both the presence of unbalance and its degree or amplitude but is of itself insufficient to permit corrective action to be taken because the site of unbalance is still unknown. To supply the required information, an arm or the like is caused to be driven in synchronism with the cylinder as by being mounted on the shaft 19 and driven thereby. This rotating arm, by commutator action, provides a series of electrical signals as it rotates, each signal indicating or identifying a particular segment of the cylinder. Accordingly, when the first or vibration signal is emitted, the commutator arm establishes the position of the rotating cylinder at that particular time so that all required information is supplied in electrical form. Both electrical signals are applied to an electrical network which causes selected solenoid valves to operate and automatically inject counterbalance fluid in a pocket or pockets opposite to the site of unbalance. Such injection continues while the overweight becomes neutralized whereupon the vibration signal decreases and finally is too small to actuate the electrical network. At such time injection is discontinued. If, as extraction of cleaning fluid from the articles proceeds, sufficient vibration is again produced due to subsequent unbalance whether ascribable to changes in weight distribution or to greater centrifugal forces generated by successive high speeds of rotation, the actuating vibration signal is re-established and corrective action is automatically re-instituted.

60 In addition to the above functions, the circuits disclosed prevent full speed rotation of the cylinder until a satisfactory degree of balance is achieved. This is accomplished by noting the duration of operation of any solenoid feed valve 75 and intermittently cutting off the motor 18 if

such duration exceeds an arbitrary, predetermined time. In other words, if a pocket of the cylinder is receiving fluid to correct unbalance, it is undesirable to proceed to higher speed until corrective action is taken since the unbalance may be excessive and cause injury to the machine. Accordingly, the continued operation of the solenoid feed valves is arranged to cause intermittent cessation of motor operation, the circuit further acting to resume constant motor operation and accelerated speeds when the feed valves are no longer injecting fluid for sustained periods.

In order to determine the presence of unbalance, a crystal pick-up 75 or the like may be utilized, as shown in Figs. 2 and 4 and may be supported from the floor although an alternative support and modified mounting are described hereinafter. It is apparent, however, that any equivalent device such as a magnetic or a strain gauge pick-up may be used as may be an electrical switch as will hereinafter appear. The electrical output of the pick-up, as is well understood, is alternating current of substantially sine wave form produced pursuant to the vibration of the cylinder 17 in a condition of unbalance.

Referring to Fig. 4, the pick-up 75 generates electrical voltages through the action of the crystal 76 and such voltages are applied to the control grid 11 of a vacuum tube 78. Tube 78 is illustrated as being a pentode so as to achieve high gain but it is evident that any amplifying tube may be employed. The condensers and resistors shown in the tube circuit provide conventional grid bias, screen grid voltage and by-pass and control grid leak resistance according to principles which are well understood in the electronic art, and which need not, therefore, be further described. Voltage for plate 79 is secured through wire 80 through plate load resistor 81. Wire 80 is connected to one side of choke 82 which, as will be recognized from the rectifier 83, is a positive source of voltage. Rectifier 83 is a conventional full wave rectifier which converts the voltage of transformer 84 to direct current, the switch 85 applying the alternating voltage to the transformer. The secondary 86 of transformer 84 is employed to energize the heaters of the tubes. However, any suitable source of current may be employed.

Vacuum tubes 87 and 88 are fed by vacuum tube 78 and function to cut off operation of the apparatus when unbalance exceeds a predetermined level as will hereinafter be described. Tube 78 feeds the vibration signals through coupling condenser 89, wire 80 and wire 91 to the three valve control vacuum tubes 92, 93 and 94.

Tubes 92, 93 and 94 form part of a valve control system and are illustrated as being gas filled discharge tubes of the thyratron type although it will be recognized that many other types of vacuum tubes may be employed. The function of tubes 92-94 is to close the circuit of the electro-magnetic windings 95, 96 and 97 of the feed valves 26, 27 and 28 so as to control the flow of counterbalancing fluid through the pipes 29-31. Tubes 92-94 are phase-controlled so as to operate upon a predetermined coincidence of plate and grid voltage. Whereas the grid voltages are supplied through the operation of the pick-up 75, the plate voltages are supplied by a commutator or distributor disc 98 which is maintained stationary in the housing 99 as shown in Fig. 1.

Commutator disc 98 (Fig. 4) contains three segments 100, 101 and 102 which are of electri-

cally conductive material and separated by insulating material. For example, each segment may occupy about 110 degrees of a circle while the insulating areas occupy about 10 degrees each. Commutator arm 103 is connected to shaft 19 so as to rotate therewith and effect consecutive electrical contact with the stationary commutator segments. It is evident, however, that the disc may rotate and the arm may be stationary since only relative rotation is necessary.

Spring-biased contact 104 bears against the hub of arm 103 and may take the form of a conventional electrical brush. Wire 105 is connected to contact 104 so as to apply thereto the B plus voltage derive 1 from point 106 of the power supply. As an example, this may be in the neighborhood of 300 volts. Wires 107, 108 and 109 are connected through the plate load circuits to the plates of tubes 92-94. In this manner, the commutator which makes one revolution for every revolution of the cylinder thus acting as a reference multiple switch, successively applies operating plate voltages to the tubes 92-94 and removes such voltages as the arm 103 leaves any one of the segments.

It will be recognized from the foregoing that any one of the tubes 92-94 will conduct current according to the phase relationship or time coincidence of the grid and plate voltages. Inasmuch as the voltages applied to each plate are periodically cut off, it may be considered that the plate supplies consist of alternating voltages of square wave form. Since the phase of the grid voltage will depend upon the site of unbalance, variations of such site will vary the relative phase of the two voltages on each tube, that is, the relative time at which they reach their peak values. If the phase of the grid voltage lags the plate voltage by 180 degrees, the plate current will be entirely cut off. When both the grid and the plate of any tube are positive, plate current will flow, the positive value of grid current depending upon the firing voltage in the tube as determined by its constants and bias. The same action may be achieved by employing negative grid voltage as where the de-energization of a tube releases a relay or the like which closes the circuit to an electro-magnetic control valve of the type disclosed herein.

Bias for the tubes 92-94 is supplied by potentiometer arm 115 which thereby functions as a sensitivity control inasmuch as it sets the level at which the control tubes will operate. In order to provide for stability of operation, the grid bias voltage may be secured from a regulated source of voltage. This is illustrated as proceeding from dropping resistor 116 which is connected to one side of the high voltage winding of the transformer. Resistor 116 is connected to selenium rectifier 117 which supplies direct current through the regulating resistor 118 to the voltage regulator tube 119. Tube 119 may be of the type VR75. Resistor 120 serves to limit the current flow. Arm 115 may be set, for example, to bias the control grids of tubes 92-94 to 20 volts negative depending upon the output amplitude of amplifier tube 78 at which corrective action should be taken.

In order that tubes 92-94 be not operated by shock generated or transient voltages, a filter condenser 121 may be supplied. This filter condenser is more or less representative of any required type of filter which may be as elaborate as necessary. For example, a two or three stage filter circuit as employed in well filtered power

supplies may be used. Condenser 121 may be in the order of .01 microfarads. Shock voltages are generally of high frequency whereas the signal voltages applied to the grids are in the neighborhood of 15 cycles per second or less so that the filter condensers 121 may be rendered effective in grounding the undesired shock voltages while having relatively little effect on the desired signal voltages.

As heretofore explained, arm 103, being keyed to the shaft 18, constantly maintains an angular position, which is related to the angular positions of the pockets 21, 22 and 23, or to the segments of the cylinder which they represent. Accordingly, because the cylinder and pockets turn with the shaft as does the arm 103, the time of application of the plate voltages to tubes 92-94 will establish the momentary position of such pockets or segments. Such establishment of the angular position of the pockets is combined, as aforesaid, with the amplitude of unbalance voltage so as to cause the counterbalance fluid to flow to the required pockets.

Referring to Fig. 6, the square wave 125 may represent the plate voltage on tube 92, the duration of such application of plate voltage depending upon the arcuate length of the segment 100 of the commutator disc. As arm 103 leaves segment 100, the square wave terminates and approximately 10 degrees later the voltage is applied as square wave 126 to the plate of tube 94. In the same manner, square wave 127 is thereafter applied to tube 93 through segment 102. The cycle thereupon repeats itself as illustrated in Fig. 6. Each square wave represents a pocket of the cylinder and the waves repeat in the order of 1, 2, 3, 1, 2, 3, etc. Thus, a continuous series of pocket or segment identifying signals is provided in cyclical form as the cylinder rotates.

At the same time the plate voltages are successively applied to the three tubes in any one cycle, the pick-up voltage 128 which is generally of sine wave form, is applied to the control grids. If the crest 129 of the sine wave is applied to the grid during the same period of time that square waves 126 and 127 are applied to the plates of tubes 93 and 94, then both tubes 93 and 94 will fire and will open their associated valves so as to supply counterbalance fluid to two of the pockets, such pockets being 22 and 23. It will be evident that if the crest 129 were to be advanced a few degrees because of a shifting of the overweight, only tube 93 would be actuated and only its associated pocket would be fed. Fig. 6 illustrates the fact that two pockets may be fed simultaneously pursuant to a specific state of unbalance. This is of considerable importance as otherwise the filling of one pocket at a time causes delay and prolongs balancing operations whereas filling of two pockets in certain cases prevents such occurrences by taking care of most sites of unbalance simultaneously.

The firing voltage 130 depends upon the setting of the sensitivity control 115. Any of the tubes 92-94 will fire when the voltage on the grid exceeds such firing voltage while the plate voltage is applied. The tubes 92-94 control the operation of valves 26-28 in the following manner:

Assuming that commutator arm 103 is in contact with segment 100 so that tube 92 is provided with plate voltage and assuming further that at that very time the grid voltage amplitude reaches the firing voltage, tube 92 will become conductive. Considerable plate current will flow through tube

92 so as to energize relay 135. Armature 136 will thereupon be drawn inwardly so as to close contacts 137 and 138.

Electromagnet winding 95 (Fig. 4) will be energized through wires 139 and 140 connected to the primary or power transformer 84. It will be understood that electromagnet 95 is a winding of a conventional A. C.-operated solenoid valve 26. At this point, fluid from pipe 55, Fig. 1, will be supplied to pipe 29, jet 32, feed ring 35, and pipe 36, into pocket 21. The fluid will therefore be correctly applied so that the cylinder approaches a state of balance. As the counterbalance fluid pours into the pocket, the amplitude of the grid voltage will decrease as the vibration decreases pursuant to the correction of unbalance. When the amplitude is such as to descend below the firing voltage 130, tube 92 will extinguish notwithstanding the coincidence of the plate and grid voltages. It is a recognized characteristic of gas-filled tubes of the thyratron type that removal of grid firing voltage alone does not per se produce tube extinction. However, the described method of removing the plate voltage by the commutator action insures proper extinction of the tube since it is well known that the absence of plate voltage will produce this effect.

If ordinary vacuum tubes of the power amplifier type are employed, the plate voltage may be continuous and constant, while the phase of the grid voltage will determine the particular tube or tubes which will conduct current so as to operate the solenoid valves, as set forth in our above-mentioned previous application.

The commutator segments are generally spaced approximately 10 degrees apart in order to decrease the angular sensitivity of the system so as to avoid overcompensation when the unbalance is slightly displaced from a position opposite a pocket. Referring to Fig. 6, it will be evident that if the crest of the grid voltage were shifted slightly from time coincidence with one square wave to another, the margin or spacing provided between the successive square waves prevents corrective action so that the angular sensitivity is decreased. It has been found, in fact, that 30 degree commutator segments separated by 90 degree areas is satisfactory. The tubes 93 and 94 function in the same manner as tube 92, and one or two of the tubes, but not all of them, may function simultaneously as will be observed in Fig. 6.

Inasmuch as the relay 135 is operated only when a pocket is being filled, it affords means to provide visual evidence of the operation of the balancing system. Accordingly, an armature 145 is provided which, upon closing contacts 146 and 147, provides energizing potential for pilot light 148 through the transformer secondary 86.

A modification, not shown, of the electronic control unit which employs but one thyratron tube, instead of the three shown in Fig. 4, is feasible and has apparent advantages. Thus, the leads to the plates of tubes 92, 93 and 94 are tied together and are connected to the plate of the one thyratron tube. The control grid of the tube is connected to the coupling condenser 89 while the cathode is connected to ground in the usual manner. This substantially completes the circuit in combination with the remainder disclosed.

In order to insure complete de-ionization of the tube before the brush starts commutation on the succeeding segment after the tube has been fired, it is necessary that the segment insulating areas or air gaps be greater than the brush width by an amount sufficiently large to insure interrup-

tion of the plate voltage for the de-ionization time of the thyratron, as will be evident to those skilled in the art.

The electrical components above described are maintained in a housing 149 which may be disposed on the shell or housing 50A. The three lamps or pilot lights 148, 150 and 151 will light according to which of the pockets is being filled at any particular time.

Since the tubes will successively extinguish as the commutator arm rotates, under ordinary conditions the valves would be de-actuated between firing periods so that counterbalance fluid would only flow when the tube was firing and, therefore, would flow in spurts, that is, the control valves would open only once for each revolution of the cylinder, and in addition might chatter and wear excessively. It is important to avoid such periodic action and to maintain a continuous flow and means are therefore provided to continue the action of the solenoids for a period after the tube associated therewith has been extinguished and at least until the tube re-fires when the plate voltage is re-applied thereto.

This is accomplished by providing holdover circuits in the form of condensers 155, 156 and 157 effectively disposed across the respective relay windings. The commutator action will charge each condenser at the same time that the plate voltage is applied to the tube associated therewith so as to fire the tube. When the source of voltage is removed, the condenser will maintain energization of the relay by discharging therethrough. The capacity of condensers 155, 156 and 157 is chosen so as to produce a time constant network which is correlated with the lowest speed of cylinder rotation at which balance is desired. It is apparent that if the cylinder rotates 5 times a second at minimum extraction speed, for example, the time constant may be in the order of one-fifth of a second and the holdover circuit elements will be selected according to well known standards. By this means, when the correct pocket or pockets have been established for the introduction of counterbalance material, the application of such material will be continued to such pocket until balance is achieved notwithstanding the periodic extinction of the tube which controls the valve. Resistors 160 and 161 are current limiting resistors which may have approximate values of 5000 ohms and 15 ohms respectively. The time constant may be set to correspond to the lowest speed of extraction operation at which balance is desired. However, if it is desired to render the time constant somewhat proportional to rotation speed, the resistor 161 may be increased to 1500 ohms or so, so that the condenser charges less at high speeds since the arm 103 passes the commutator segments more swiftly and condenser is thus given less time to charge; accordingly, its hold-over time will be correspondingly less. It is also feasible to employ dash pots built into the cores of the relays so as to produce a mechanical or hydraulic delay of the closing of the control valves.

Although a cylinder having three pockets has been shown, it will be obvious that many more such pockets may be provided if finer degrees of balance are to be achieved. In such cases, the commutator would be provided with contacting segments of a number commensurate with the division of the number of pockets into 360 degrees, as will be evident.

Means are provided to discontinue operation of the cylinder when the unbalance is so great as

to be potentially injurious to the machine. For this purpose, the output of amplifier tube 18 is caused to shut off the motor when such output exceeds a predetermined level. The output of tube 18 is applied through condenser 165 to rectifier tube 87. The output of tube 87 is essentially an automatic volume control circuit, as will be evident. However, it is not used as such but serves to apply a control voltage to tube 88. Potentiometer arm 166 is set according to the level at which operation should be discontinued. Normally, tube 88 will be passing current and the electromagnet 167 which is in its plate circuit attracts armature 168 so as to maintain the contacts 169 and 170 normally closed. Thus, the extractor motor cannot be started until the tubes of the electronic unit have heated to operating temperatures. Upon a high amplitude signal from rectifier 87, tube 88 is cut off and armature 168 is released. Contacts 169 and 170 which normally maintain terminals C and D closed, thereupon open the circuit and cut off operation of the motor, as will be described in connection with Fig. 5.

The instant invention comprehends the provision of a motor control circuit which serves to render the aforescribed balancing system more effective. A primary feature in such motor control circuit is to disable motor operation intermittently during prolonged periods of balancing through fluid injection. Inasmuch as the motor, or a clutch rotates the cylinder at extremely high speeds, it would not be desirable to permit unrestricted acceleration during a marked degree of unbalance even while such unbalance is being corrected. This, as well as other improvements in the operation of the system are provided by the control circuit illustrated in Fig. 5.

Terminals A and B shown in Fig. 5 are connected to the correspondingly lettered terminals of Fig. 4, while the terminals C and D are likewise connected to the C and D terminals of Fig. 4. Motor 18 is disclosed as a three phase motor operated through the lines 200, 201 and 202. The components shown, enclosed in the broken line area 203 are those of a conventional magnetic starter for electric motors. In order to adapt such a starter to the required operation of the instant apparatus, wires 204 and 205 of the magnetic starter are broken and the armature or contact 206 of time delay relay 207 is inserted thereto. Wires 208 and 209 are provided with a push button starting switch 210 which is normally in the open position shown. Winding 211 is the conventional coil of the magnetic starter which normally maintains armatures 212-215 open. When winding 211 is energized, pursuant to the conventional action of such magnetic starters, these armatures close the circuit and permit operation of the motor 18 through the three phase lines. Heaters 216 and 217 operate the thermo-switches 218 and 219 respectively so as to provide thermal overload circuits for cutting off the motor under conditions of a short circuit or the like.

Switch 220 is a stop switch which is normally closed and permits the apparatus to be shut off at the will of the operator. Relay winding 221 having armatures 222-224 is provided to maintain a closed circuit for time delay relay 207 when any control tube of Fig. 4 is operating a feed valve, as will be hereinafter set forth. The following describes the operation of the motor control circuit, it being presumed that the electronic unit, schematically illustrated in Fig. 4, and

housed in the case 149 (Figs. 1 and 2) is in operation.

Referring to Fig. 4, when winding 135 is energized indicating that feed valve 26 is operating and pocket 21 is being filled, relay contacts 230 and 231 close. This shorts the terminals A and B so as to close the A B circuit. The same action results when any of the other control tubes are operating, so that A and B are shorted during the filling of any pocket.

Referring now to Fig. 5, terminals C and D are normally closed as above stated, and only open under such large degrees of vibration as warrant shutting off the motor and re-distributing the articles. Thus, C D may be considered to be closed during conventional operation.

Lines 201 and 202 of the three phase lines provide operating voltages for the motor control relays above described. Accordingly, when the normally open start switch 210 is manually depressed, as when the machine is put in operation, the operating current will travel from line 202 across C, D, the normally closed stop switch 220, the switch 210, the normally closed armature 206, and across the thermal switches to line 201. Consequent energization of winding 211 draws its four armatures inwardly so as to close the motor circuit and operate the apparatus.

Closing of start switch 210 also energizes relay winding 221 which remains locked through closed armature 215. Such operation of winding 221 closes armatures 222, 223 and 224, so as to permit time delay relay 207 as well as master valve 54 to be energized upon closing of the A, B circuit. In addition, solenoid winding 226, which is a solenoid operated friction brake against the shaft 19, is also energized. Such friction brake is operative in the absence of energizing current, but energization of the winding, as by closing the start switch, withdraws the brake. This action is conventional and forms no part of the instant invention.

Time delay relay 207 is provided to achieve intermittent operation of motor 18 during times when the pockets are being filled. As above stated, it is desirable to avoid full speed operation of the motor under a marked condition of unbalance in order to avoid excessive vibration, personal danger, and possible damage to the apparatus. This objective has been realized by interrupting operation of the motor if any control tube 92-94, or combination of control tubes, operates for more than a predetermined time, for example, three seconds. If the three second interval during which the control tube operates is insufficient to fill a pocket to balance requirements, the time delay relay 207 opens the motor circuit until the control tubes extinguish. If an external source of fluid is being used, as, for example, the municipal water supply at its own pressure, the motor may thus be cut-off more or less frequently and may coast for longer or shorter periods, depending upon the pressure, and, therefore, the rate at which the pockets are being filled. Such operation is valuable as a safety measure inasmuch as variations in fluid feeding pressure cannot affect the expedient of avoiding motor speed-up while unbalance is present. It will be noted that the balancing operations occur principally at speeds less than full speed or during acceleration of the motor. When the cylinder has attained full speed rotation, only small amounts of counterbalance fluid will be required to maintain such balance as the

cleaning fluid is extracted from the articles and, therefore, changes the weight distribution.

It is necessary, in the form being described, that when the control tubes extinguish and terminals A, B open, the time delay relay 207 must automatically reinstitute operation of the motor. Accordingly, the action thereof is to be distinguished from the action of the stop switch 220 which cuts off motor operation so that it can only be reinstated by manual operation of start switch 220. The disclosed time delay circuit accomplishes the automatic intermittent starting of motor 18 whereas the normal action of the magnetic starter is to cut off the motor until the operator puts it back in operation by manually actuating the start switch.

Relay 207 is of a conventional type having a three second time delay in operation and a substantially immediate reset time. When terminals A, B are shorted, indicating the presence and correction of unbalance, the time delay relay, after a three second interval, opens armature 206 so as to de-energize coil 211, and open the circuit to the motor and discontinue its operation. Relay winding 221 remains closed, however, so as to maintain the time delay relay circuit and the brake circuit likewise closed. When the control tube extinguishes, and terminals A, B open, the time delay relay 207 becomes de-energized and armature 206 returns to its normally closed position, re-energizing the magnetic starter coil 211 and re-instituting motor operation automatically.

With the provision of the foregoing motor control circuit, each control tube operates in normal fashion, but the motor 18 cannot bring the cylinder up to full speed during such a condition of unbalance as requires more than three seconds of continuous counterbalance fluid feeding time. Inasmuch as three seconds is not sufficient time for the motor to rise to full speed, unbalanced full speed operation is prevented. The motor cuts in and out automatically according to the operation of the control tubes although the stop switch 220 is nevertheless operative in its normal manner to discontinue operation of the motor without danger of its automatically starting because of the time delay circuit disclosed. The three second interval is, of course, variable over a very wide range depending upon the size of the feed valves and the degree of pressure in feeding the fluid as well as the size of the machine.

It will be understood that the time delay relay takes effect many times during the extraction operation as the speed increases or as the balance varies through extraction of fluid. For example, a condition of unbalance at one speed may be corrected for that one speed but as the speed increases that same condition may re-actuate the balancing elements because of the increase of centrifugal forces or the effective re-distribution of the weight within the cylinder through the varying losses of fluid in the soaked articles.

Valve 54 which is in the supply pipe line as disclosed in Fig. 1, closes when terminals A, B are shorted so that said valve is open when any of the solenoid valves 26-28 are open and it closes when one of those valves is closed. This expedient is provided in the event that any of the closed control valves leak, such leakage being guarded against by the precaution of maintaining valve 54 closed at that time. If a pump is used to supply the fluid pressure, its motor may take the place of valve 54 so as to be operated in like manner as explained hereinafter.

The above apparatus provides a balancing system for extractors per se or in either washing or dry cleaning machines or the like which may include a tumbling operation and which effect extremely high speed operation of the rotating cylinder so as to realize the advantages of high speed extraction generally set forth above. Due to the balancing action of the apparatus, substantially higher speeds are feasible while the installation of a machine of this type is facilitated and elaborate mountings in floor supports are unnecessary.

Figure 7 illustrates a machine generally similar to that of the foregoing figures and applicable toward the correcting of dynamic unbalance in an elongated double bearing machine. The balancing system is applied at both ends of the elongated cylinder rather than to one end. Other modifications are likewise disclosed.

In Fig. 7, the cylinder 250 is rotatably housed in a stationary shell 251. The cylinder is rotated by its trunnions 252 which are actuated by a driving motor, not shown, and rotate in anti-friction bearings 253. Each end of the shell 251 has separate and independently operating pickups 254 and 255. The action of the pick-up 254 determines the flow of counter-balance fluid through the feed ring assembly 256 in the same manner as shown in Fig. 1. Thus, the feed pipe 257 functions as does pipe 29 while other pipes feed the other feed rings. Each feed ring is further provided with a feed pipe 258.

The cylinder 250 is provided with two end sets of outside elongated pockets, each set consisting of three in the form shown. Referring to Fig. 8, 35 the three pockets 260, 261, and 262 are angularly disposed around the outside of the cylinder in equally spaced relationship. Pocket 260 receives the counterbalance fluid from pipe 258 through chamber 264. Chambers 264, 265 and 266 in the aggregate occupy substantially the entire circumference of cylinder 250. Each chamber communicates with its associated pocket and is separated from the other chambers by partitions 267. The floors 268 of the chambers terminate short of the partitions so as to provide a discharge outlet 271 for counterbalance fluid after the extraction is terminated and the rotation speed of the cylinder materially decreases. The chambers extend to the periphery of the cylinder and counterbalance fluid will be initially directed toward such periphery by centrifugal force. Thus, the chambers are effectively disposed adjacent angularly spaced peripheral portions of the cylinder as are the elongated pockets.

According to a specific state of unbalance, as determined by a commutator such as commutator 98 of the previous embodiment, in cooperation with the pick-up, counterbalance fluid will flow through pipe 258 and into chamber 264. Centrifugal force generated by the rotation of the cylinder will impel the fluid away from the axis of rotation and against the periphery of chamber 264 so that the fluid will tend to spread laterally against such periphery. Accordingly, the fluid will fill the pocket 260 as it spreads from the chamber 264. This provision of endwise disposed chambers is considered to be of advantage in that a large amount of counterbalance fluid may be applied so as to accommodate large degrees of dynamic unbalance. Furthermore the fluid in the chambers contributes materially to the correction of such dynamic unbalance because the effect is confined mostly to the extreme ends of the cylinder and, when only the end 75

chambers are used as hereinafter described, the effect of added weight at one end is minimized in regard to the other end. Each feed ring assembly 266 at each end of the cylinder may feed one or two of its chambers and hollow ribs in the same general manner as in the first embodiment described. In order to isolate respective end pockets or ribs from each other when they are used, they terminate in rear walls 269 and an intermediate area 270 does not receive counterbalance fluid. This space 270 is variable and may be of greater length so as to maintain the balancing fluid as close to the bearing 253 as will permit and still provide extra space for balancing fluid for very large amounts of out of balance to be corrected. The elongated pockets, may, if desired, be dispensed with and only the endwise chambers be employed as weight receiving elements.

As cylinder rotation decreases at the end of an extraction operation, and centrifugal forces no longer maintain the fluid against the ceilings of the chambers and pockets, the counterbalance fluid will flow out of such pockets and chambers through the discharge outlets 271 formed by the openings in floors 268. Such discharging fluid will reach the shell 251 where it may be further discharged or fed through the valve 272.

It will be understood that only one commutator in the nature of commutator 98 will be required for both ends of the cylinder and such commutator may be disposed on either of the shafts or trunnions 252. The electrical circuit for each end of the cylinder will substantially duplicate that disclosed in Fig. 4. The door 273, it will be recognized, is provided so that the cylinder may be loaded with or emptied of articles.

Fig. 9 illustrates a modified embodiment of each end of the elongated cylinder shown in Fig. 7. The chamber 275 is separated from its associated pocket 276 by a wall 277. Accordingly, fluid from feed pipe 278 first fills the chamber 275 in order to correct a condition of unbalance. If chamber 275 is of insufficient volume to effect such correction, the fluid will further feed through pipe 279 and through wall 277 into pocket 276. Pipe 280 is provided as an air outlet for pocket 276. Should chamber 276 be of sufficient size for all general purposes, pipe 279 may be closed or omitted and all balancing fluid will therefore remain closer to the end bearings. In any event, the fluid receiving pockets may take the form of angularly arranged end chambers such as chamber 275 without including elongated pockets as above noted. Pipes 279 and 280 may also be water outlets.

Figures 10 and 11 disclose a modified form of pick-up arrangement which is particularly useful with the apparatus of the instant invention. Bearings 300 and 301 substantially duplicate bearings 57 and 58 shown in Fig. 1, shaft 302 duplicating shaft 19. A crystal pick-up or snap switch or the like 303 is mounted on support 304 integral with bearing 301. An arm 305 is connected to platform 306 which supports bearing 300. Bracing arm 307 may also be provided to effect further mechanical support for arm 305. The operating pin or needle 308 of pick-up 303 contacts arm 305 so that vibrations at the outer end of arm 305 generate or produce the pick-up voltages.

The advantages of the last described pick-up include the fact that the pick-up may be

mounted on the machine itself instead of being mounted on the floor as shown in Fig. 2. The cylinder attached to shaft 302 is rigidly supported in its bearings and represents an overhanging weight. The shaft, being somewhat elongated, will rock about a central point in a see-saw movement produced by uneven distribution of articles in the rotating cylinder. Thus, one end of the shaft 302 will have a component of movement opposite to the other end thereof. One end of the arm 305 is connected adjacent to one end of shaft 302 nearest the cylinder as shown although it may be attached to the shaft itself. Arm 305 is thereby caused to partake of the same movement as that portion of the shaft while the pick-up 303 partakes of the movement of the other end of the shaft. Accordingly, substantial relative movement is created between the arm 305 and pick-up 303 notwithstanding the fact that they are mounted on the same base, and such movement produces the pick-up signals through displacement of the crystal pick-up pin or microswitch button.

Bearing 301 is rigidly supported on platform 310 which is braced by arms 311 on standard 312. Standard 312 may be a vertical steel column without side braces so as not to unduly resist relative movement of the outer end of shaft 302 and permit a slight horizontal movement generated through cylinder unbalance, as above described. Tank 313, serving as a base, is similar to tank 51 of Fig. 2 while structure 314 may be the shell of the machine.

It is to be noted that the vibration pick-up action may be accomplished with a microswitch or snap switch instead of a crystal, the microswitch operating from the deflections of the bearings and functioning to make and break the electrical circuit as disclosed in Fig. 14. Thus, such a microswitch performs the required function of supplying vibration voltages without the use of vacuum tubes or similar amplification means.

Figs. 12 and 13 disclose a further modified form of pick-up arrangement in combination with variations in the physical structure of the apparatus but the form of the pick-up arrangement is not claimed herein, although the physical arrangement of the pockets and chambers is included in the instant invention. Shell 325 is supported on base 326 and is provided with a dump valve 327. Standard 328 supports hollow trunnion 329 through anti-friction bearings 330 and 331. Trunnion 329 is supported on end wall 332 of the cylinder 333. Such support is rendered slightly resilient or yieldable through the medium of a rubber pad or gasket 334 interposed between the annular flange 335 of the trunnion and the end wall 332. Rivets 336 maintain the required connection. By this expedient, the trunnion 329 is permitted a wider range of relative movement in response to vibrations of the cylinder. Rod 337 is connected to end wall 332 as by the rivet head 338 so that the rod 337 partakes of the movement or vibration of the cylinder. A pick-up 339 is disposed at the outer end of rod 337 so that variations of vibration between the trunnion or bearings and the rod are applied in physically amplified form to the pick-up although such amplitude may be regulated as described by varying the resiliency of the gasket 334. A commutator (not shown) may be employed as in the previous embodiments, so that conditions of unbalance will be corrected through the system described herein.

The feed ring assembly 340 takes the same

form as in the previous embodiments with, however, slight modifications in the form of the feed pipes and pockets. Thus, the feed pipe 341 extends into pocket 342 through auxiliary chamber 343 having an outlet discharge of the fluid after the extraction operation. Thus, a short outlet pipe 344 further directs the discharged fluid into the shell and it effectively extends the pocket or chamber opening so far to the center of the cylinder that the entrance of cleaning fluid into the pocket during tumbling and washing operations is particularly minimized.

It is evident that such undesired flow, if any, would occur principally when a guide pipe had its mouth somewhat upwardly disposed, as when it is passing along the floor of the shell. At this time fluid might be scooped into the guide pipes and to the pockets. Accordingly, and for further assurance, it is contemplated that a conventional gravity actuated ball valve (not shown) may be enclosed in a retaining wire guard over a beveled or conical mouth of each guide pipe so as to seal such mouth when it is upwardly disposed and to fall away therefrom so as to permit discharge when the mouth is above the center of the shell.

In Fig. 14 is disclosed a modification of the electronic circuits of Fig. 4. An apparatus incorporating the circuit of Fig. 14 is particularly well adapted for household uses in that it is more simply manufactured, is less expensive, and will nevertheless be entirely satisfactory for general requirements. Shaft 350 is the driving shaft for the cylinder and corresponds to shaft 19 of the first embodiment. Commutator 351 substantially duplicates commutator 98 of such first embodiment (Fig. 1). Actuating power for the relays originates at the terminals 352 and 353 and is rectified, if desired, at 354. The rectified current is fed through current limiting resistor 355 to spring arm 356 of a microswitch 351. The term "microswitch" as used in the electrical art generally refers to a snap switch which is spring-biased to either open or closed position and which is actuated by an outside force, usually mechanical. In most such switches, the force required is rather minute, depending upon the specific application.

Arm 358 is connected to switch arm 356 as part of the microswitch and is disposed adjacent to either the driving shaft, the shell or the rotating cylinder so as to be actuated thereby when the cylinder is rotating in a condition of unbalance. Such arm produces the mechanical force required to close switch arm 356 against terminal 359. It will be recognized, therefore, that switch 357 takes the place of a pick-up such as employed in the previous embodiment. It performs the same function, that of providing a vibration voltage, but such voltage originates from the source of supply represented by terminals 352, 353 instead of being generated through its inherent characteristics as does the pick-up. When the cylinder is unbalanced, it rotates eccentrically and the furthest points of eccentricity, whether of the shell, the cylinder, or machine itself, serves to actuate operating arm 358 and switch arm 356 so as to close the switch. The time then, when the switch closes, determines the site of unbalance.

Shaft 350 has the commutator arm 360 connected thereto so as to effect successive electrical contact with the three segments 361, 362 and 363. Switch terminal 359 is connected to spring contact arm or brush 364 so as to transmit the volt-

age to the commutator arm when operating arm 358 is actuated. The source voltage is thereupon applied to wires 365, 366 and 367 respectively.

Wire 365 is connected to electro-magnet winding 368, the other end of which is connected to terminal 352. Accordingly, the source voltage energizes winding 368 when commutator arm 360 is on segment 363 at the same time that arm 358 is actuated. Wires 366 and 367 respectively function to close similar circuits to windings 368 and 370 when arm 360 makes contact with segments 361 and 362 respectively. When winding 368 is energized, it attracts armature 371 so as to bring contacts 372 and 373 together. Solenoid valve 26a is thereupon energized and counterbalancing fluid is thus caused to flow into its associated pocket. It is possible for economy purposes, to eliminate the windings 368, 369 and 370 and actuate the solenoid valve windings directly providing hold-over elements in such valve windings (in the same manner as shown for the relays) as will be evident to those skilled in the art.

It will be recognized that the microswitch, in combination with the commutator forms an electrical circuit such as is formed through the electronic circuit disclosed in Fig. 4. Inasmuch as the time of the closing of the microswitch 357 must be correlated to the action of commutator 351, the phases of operation of these components determine the pocket or pockets into which counterbalance fluid is applied. As in such electronic apparatus, it is the coincidence of unbalance reaction as applied through the vibration responsive device and the commutator action which jointly close the electrical circuit so as to energize an appropriate solenoid valve when conditions so indicate.

Each electromagnet winding includes relay contacts such as contacts 374 and 375. These duplicate the function of contacts 230, 231 (Fig. 4) in closing the A, B circuit for the time delay relay 207 (Fig. 5). The electrical circuit of Fig. 14 is used in combination with the feed rings, jets and other physical elements described in the previous embodiments.

In order to insure reasonable speed and continuity in the balancing process, each electro-magnet winding in Fig. 14 is supplied with a hold-over circuit designed to continue the application of counterbalancing fluid to the correct pocket notwithstanding the fact that coincidence of unbalance reaction and reference action cannot occur when the commutator arm has left a segment which represents the site of desired correction.

The hold-over action thus substantially duplicates the hold-over circuit of the previous embodiments. The hold-over of Fig. 14 is accomplished by providing condensers such as condenser 376 across the winding 368. It will be evident that the inductance of winding 368 and the capacitance of condenser 376 create a time constant network which maintains current flowing in winding 368 for the duration of such time constant. The particular time constant will depend upon cylinder rotation as in the previous embodiment, a cylinder rotating 6 times a second, for example, requiring a time constant of at least $\frac{1}{6}$ of a second. Condensers 377 and 378 perform identical functions as condensers 376.

In Fig. 15 is disclosed a modified embodiment of a hold-over circuit which may be employed in any of the previous hold-over networks. In place of a shunting condenser or resistance, there is provided a short-circuited winding 380 which main-

tains a flow of current through electromagnetic winding 381 when the voltage directly energizing winding 381 is interrupted. Winding 380, which may consist of 1 or 2 turns, is wound on the same core as is winding 381 and it performs in the nature of what is known in the art as a shading coil. When the voltage energizing winding 381 is interrupted, winding 380 tends to maintain the flow so that contacts 382 and 383 will be held closed after winding 381 has been energized and the commutator arm has left the segment associated with the winding.

In order to provide means for shutting off the motor under conditions of excessive vibration, an additional microswitch is provided as shown in the circuit in Fig. 14. The microswitch actuating member 349 whether the driving shaft, the shell or the cylinder is caused to act against a second microswitch 384 under such excessive degrees of vibration. Arm 368 of microswitch 357 is separated from member 349 by a space 385 which represents that predetermined degree of vibration which is conveniently correctable. Space 386, between member 349 and arm 387 of microswitch 384, is larger and represents such degree of vibration as warrants discontinuing motor operation. Accordingly, when this degree of vibration is encountered, microswitch 384 will open so as to open the C D circuit. Thus, the circuit of Fig. 14 may be combined as indicated with the circuits of Figs. 5 or 5A.

In Fig. 16 is disclosed an apparatus generally similar to that shown in Fig. 1 but adding further details which are generally found in dry-cleaning apparatus. Thus, the cylinder, shell and counterbalance fluid feeding system are the same as that shown in Fig. 1. However, the complete system disclosed in Fig. 16 emphasizes the common use of cleaning fluid for both cleaning the articles and supplying the required counterbalance weight.

Tank 400, corresponding to tank 51, contains a supply of cleaning fluid which is drawn up through pipes 401 and 402 through the action of pump 403. From pipe 402, the counterbalance fluid is applied to the feed rings and pockets pursuant to the control system heretofore disclosed. A filter mechanism and tank 404 is arranged to communicate with tank 400 through pipe 405 by opening valve 405A and closing valve 408A. Tank 404 may then supply fresh cleaning fluid to the shell 406 through the pipes 407 and 408, valve 408A being then opened and valve 405A being closed.

Pipe 409, including the valve 410, serve to discharge used or contaminated synthetic fluid from the shell into the tank 411 from where it is pumped by pump 412 through pipe 413 into the filter 404. Pipe 414 is the usual overflow pipe used to discharge any excess fluid directly into the tank 411. A pipe 415 and valve 416 are provided so as to permit an interchange between the fluid in tank 411 and that of tank 400, when desired. It will be understood, therefore, that the cleaning fluid may be used as the balancing fluid originating as they do from common sources and flowing through common lanes of supply and discharge.

As an alternative method of employing the master valve 41, a relatively small by-pass pipe 425 (Fig. 16) is further disclosed as shunting the master valve but is not claimed in the present application. This construction may be employed in conjunction with the circuit of Fig. 5A. As noted in Fig. 5A, an armature 426, controlled by

time delay relay 207, is in series with the winding of valve 54. Valve 54, in the modification now described, is normally de-energized and closed during all times save when time delay relay 207 takes effect so that counterbalance fluid is not fed therethrough but rather through the by-pass 425. When time delay relay 207 is operated after the predetermined three second interval or the like, the master valve 54 becomes energized and opens so as to admit a considerable quantity of balancing fluid supplementing the by-pass fluid supply which is relatively small. The purpose behind such action is to procure fine degrees of balance although avoiding undue delay in so doing. Thus, if only a slight flow is required to obtain a balance, it may be accomplished within the delay time of master valve 54 so that valve 54 need not operate while the required small amount is applied. If the unbalance is greater, the master valve will cut in after the delay interval and inject the large quantity at this time cutting off and decelerating the motor until satisfactory balance is obtained. Automatic acceleration then takes place and thereafter slight changes in weight distribution are again correctable by the by-pass 425. A hand operated valve 427 is provided in the by-pass pipe 425 to manually regulate the flow through the by-pass.

An improved and alternative method of employing by-pass 425 is permitted through the use of a solenoid valve 428, the electrical hook-up of which is disclosed in Fig. 5B.

It has been determined that this method is of advantage in achieving even finer degrees of balancing, minimum or practical elimination of hunting, and freedom from disturbance by transients. Such method is herewith described but is not claimed in the instant application.

Referring to Fig. 5B, a relay 429 is disclosed as being in parallel with the time delay relay 207 so as to be actuated when the vibration causes the AB circuit to close. Relay 429 is also of the slow closing type and a suitable time constant therefor is one second or the like. Accordingly, one second after the AB circuit has closed, the armature 430 will close the electrical circuit of solenoid valve 428. Solenoid valve 428 normally maintains the by-pass closed and when it is energized, it opens the by-pass. Hence, counterbalance fluid flows through the by-pass 425 after one continuous second of vibration signals. If the unbalance can be corrected within the following two seconds, relay 207 will not attract its armature 426a so as to open valve 54. If, on the other hand, the by-pass flow is insufficient, valve 54 will be opened and a large amount of counterbalance fluid will flow to the indicated pocket or pockets. It will again be observed that as the master valve 54 operates, the motor 18 is cut off by the action of relay 207 so as to permit the motor to decelerate or coast. At this time, large amounts of balancing fluid are applied to correct the out-of-balance occasioned by the unsymmetrically distributed fluid-soaked clothes. After balance is obtained, the motor resumes operation and accelerates toward the higher speeds. In general, large amounts of balancing fluid will be required principally at the beginning of the extraction cycle, at which time the clothes are heavily water-soaked. Thereafter, the by-pass 426 will ordinarily suffice for injecting the required balancing fluid and will serve to obtain a fine degree of balancing as well as a minimum of hunting. It will be understood that as the motor accelerates, the increased centrifugal force or

vibration will again close the AB circuit particularly since liquid is extracted from the articles so as to effectively change the weight distribution.

The short delay accomplished by relay 429 has as its purpose the elimination of actuating effects by transient or extraneous vibrations or voltages. It will be evident that cylinder unbalance which causes the closing of the AB circuit is a relatively constant condition until corrected and it is this signal which should be used to institute corrective action. On the other hand, any extraneous or transient stimulation should be disregarded in instituting the injection of counterbalance fluid. When the AB circuit is closed for about one second or the like so as to actuate relay 429, the effect of momentary transients is eliminated.

The provision of the by-pass which feeds counterbalance fluid at a much lesser rate than the valve 54, is of advantage in preventing hunting by counterbalancing more than is necessary, particularly were a heavier fluid, such as synthetic solvents or mercury, to be employed as the counterbalancing medium. This is particularly true if a fixed time constant for hold-over action on the feed valves is employed since at higher speeds the time constant has greater effect. However, the time constant may be made variable as above described.

Referring to Fig. 5B, it will be observed that the pump 403 is disclosed as a motor winding which is in parallel with the by-pass solenoid 428. By this arrangement, the pump is only rendered effective when the by-pass valve or master valve is operating. This has some advantage of minimizing leakage as by avoiding pressure on the valves except when fluid is being fed.

What is claimed is:

1. Balancing apparatus for a rotatable hollow cylinder of a machine for treating discrete articles comprising a plurality of weight receiving elements arranged to house varying amounts of weight counterbalance material, said weight receiving elements being angularly disposed around said cylinder so as to differentially affect the balance thereof pursuant to the varying amounts of said material housed therein, inlet control means including an electrical circuit for selectively varying the amounts of said material housed in said receiving elements, a vibration responsive device arranged to provide an electrical voltage pursuant to the passage of an overweighed portion of the rotating cylinder, reference means continuously operative during the rotation of the cylinder for registering the momentary angular disposition of each weight receiving element, said inlet control means being controlled jointly by said vibration responsive device electrical voltage and the action of said reference means so as to vary the amounts of said material in one or more of said weight receiving elements depending upon the site of said overweighed portion, and a plurality of feed rings rotating with the cylinder and each associated with one receiving element, said feed rings being arranged to receive liquid counterbalance material from a source thereof and feed it to an associated element, said feed rings being formed with continuous annular openings so as to receive injected material during rotation thereof.

2. Apparatus according to claim 1 and wherein in each of said feed rings is eccentrically disposed relative to the rotation axis of said cylinder, the feed rings being formed with a discharge open-

ing at the furthest point of eccentricity so that said injected material collects at said discharge opening by centrifugal action, each of said discharge openings communicating with the respective weight receiving elements.

3. Balancing apparatus for a rotatable hollow cylinder comprising a plurality of weight receiving elements arranged to receive liquid weight counterbalance material from a source thereof, said weight receiving elements being respectively disposed adjacent spaced peripheral portions of said cylinder so as to differentially affect the balance thereof when said material is selectively applied thereto, inlet control means for selectively applying such material to such receiving elements, a vibration responsive device arranged to provide an electrical voltage at a time coinciding with the passage of an overweighted portion of the rotating cylinder, and including reference means operative by the rotation of the cylinder for registering the momentary angular disposition of each weight receiving element, said inlet control means being controlled jointly by said vibration responsive device and said reference means so as to apply said material to one or more of said weight receiving elements which are in a portion of said cylinder substantially opposed to said overweighted portion, said reference means comprising a stationary distributor ring divided into a number of segments corresponding to the number of weight receiving elements, a distributor arm fixed to the cylinder so as to rotate therewith, said arm travelling over said distributor segments, means to connect a source of electrical voltage to said distributor arm whereby each of said segments is consecutively connected to said voltage source and so that contact of said distributor arm with any one segment registers the position of a particular weight receiving element.

4. Apparatus according to claim 3 and including channel-shaped, substantially annular feed rings connected to each weight receiving element so as to feed said counter-balance liquid thereto, said feed rings being connected to the cylinder so as to rotate therewith, and jet means for injecting said liquid into the channel of said feed rings according to the selection of said inlet control means whereby said liquid is transferred to said weight receiving elements.

5. Apparatus according to claim 4 and wherein each of said feed rings is eccentrically connected relative to the rotation axis of the cylinder, each of said feed rings being formed with a discharge opening at the furthest point of eccentricity so that the injected liquid tends to collect at said discharge opening through centrifugal action, said discharge openings communicating with respective weight receiving elements.

6. Balancing apparatus for a rotatable hollow cylinder comprising a plurality of weight receiving elements arranged to receive counterbalance liquid from a source thereof, said weight receiving elements being respectively disposed adjacent spaced peripheral portions of said cylinder so as to differentially affect the balance thereof when said liquid is selectively applied thereto, inlet control means for selectively applying such liquid to said receiving elements, a vibration responsive device arranged to provide an electrical voltage at a time coinciding with the passage of an overweighted portion of the rotating cylinder, reference means operative by the rotation of the cylinder for registering the momentary angular

disposition of each weight receiving element, said inlet control means being controlled jointly by said vibration responsive device and said reference means so as to apply said liquid to one or more of said weight receiving elements which are in a portion of said cylinder substantially opposed to said overweighted portion, and supplementary weight receiving chambers angularly distributed around the cylinder and connected to each weight receiving element, each of said chambers being substantially adjacent each other and having an angular disposition corresponding to that of its connected receiving element, partitions separating the chambers, conduit means operating as the connection between each chamber and its receiving element so that said liquid may be transferred from each chamber to its connected receiving element, each of said receiving elements having a lower discharge opening formed therein, feed rings connected to each chamber so as to apply said liquid thereto, and jets connected to the liquid source of supply through said inlet control means so as to selectively inject said liquid into the feed rings.

7. Apparatus according to claim 6 and wherein said feed rings are channel-shaped and are eccentrically disposed relative to the rotation axis of the cylinder while rotating therewith so that injected liquid tends to collect at the furthest point of eccentricity through centrifugal action, the connection of each feed ring to its associated chamber being effected through a discharge opening formed at said furthest point of eccentricity.

8. Balancing apparatus for a rotatable hollow cylinder comprising a plurality of weight receiving elements arranged to receive counterbalance liquid from a source thereof, said weight receiving elements being respectively disposed adjacent spaced peripheral portions of said cylinder so as to differentially affect the balance thereof when said liquid is selectively applied thereto, an inlet and inlet control means for each weight receiving element including an electrical circuit for selectively applying such liquid to said receiving elements, a vibration responsive device arranged to produce an electrical voltage having one voltage peak during each revolution of the rotating unbalanced cylinder and occurring at a time coinciding with the passage of an overweighted portion of the rotating cylinder, reference means for establishing the identity of any one of said receiving elements as the receiving element passes a predetermined line during its rotating travel, said reference means being operative to produce a series of voltage peaks each corresponding to one of said receiving elements, said reference means voltage peaks successively following each other in time and having a higher frequency than said vibration voltage whereby the time duration of said vibration voltage peak may cause it to overlap more than one reference means voltage peak depending upon the phase relationship, said inlet control means being operated by a time coincidence of a vibration voltage peak and a reference means voltage peak so as to apply said liquid to the receiving element whose reference means voltage peak coincides with the vibration voltage peak in any one rotation of the cylinder, whereby the liquid may be simultaneously fed to more than one receiving element, the vibration voltage being of substantially sine wave form and of the same frequency as that of the rotating

cylinder so that its peak occupies almost one half of the rotating cycle, said reference means voltage peaks being at least three in number and being equally spaced through said rotating cycle, and including a sensitivity control for said inlet control means, said sensitivity control predetermined the amplitude of said vibration voltage peak required to operate said inlet control means.

9. Balancing apparatus for a rotatable hollow cylinder for housing discrete articles to be treated, said apparatus comprising a plurality of weight receiving pockets arranged to receive counterbalance liquid from a source thereof, said pockets being respectively disposed adjacent spaced peripheral portions of said cylinder so as to differentially affect the balance thereof when said liquid is selectively applied thereto, inlet controls for applying said liquid to respective and selected pockets, a vibration responsive device arranged to produce a first electrical voltage at a time substantially coinciding with the passage of an overweighted portion of said cylinder whereby said first voltage is repeatedly produced during unbalanced rotation of the cylinder and varies in phase depending upon the site of unbalance, a reference multiple switch rotating with the cylinder for successively producing a series of electrical voltages of constant phase each corresponding to the angular position of a particular pocket, a control circuit responding to the coinciding application of said first electrical voltage and one of said series of voltages for operating at least one of the inlet controls so as to inject said liquid into an associated pocket, said control circuit being continuously operable during rotation of said cylinder so as to vary the inlet operation depending upon a further coincidence between said first electrical voltage as its phase may vary during changes of unbalance sites and one of said series of constant phase voltages.

10. Balancing apparatus for a rotatable hollow cylinder comprising a plurality of weight receiving pockets arranged to receive counterbalance liquid from a source thereof, said weight receiving pockets being respectively disposed adjacent spaced peripheral portions of said cylinder so as to differentially affect the balance thereof when said liquid is selectively applied thereto, inlet control means for selectively applying such liquid to said receiving pockets, a vibration responsive device arranged to provide an electrical voltage at a time coinciding with the passage of an overweighted portion of the rotating cylinder, a reference disc divided into angular segments equal in number to the number of receiving pockets, means associated with said disc for deriving a series of second electrical outputs each corresponding to one of said pockets, said inlet control means comprising an electronic tube circuit including an electronic tube and solenoid valve for each pocket, said solenoid valves being operative to transfer liquid from said source to an associated pocket, means to apply said first electrical output and one of said series of second electrical outputs to the input of each electronic tube, said tube being phase-controlled so as to pass an operating amount of current for the solenoid valve in its circuit when said first electrical output has a predetermined phase relationship with said one of said series of second electrical outputs whereby counterbalance liquid is caused to flow through the operated solenoid valve into its associated pocket.

11. Balancing apparatus for a rotatable hollow cylinder comprising a plurality of weight receiving pockets arranged to receive counterbalance liquid from a source thereof, said weight receiving pockets being respectively disposed adjacent spaced peripheral portions of said cylinder so as to differentially affect the balance thereof when said liquid is selectively applied thereto, inlet control means for selectively applying such liquid to said receiving pockets, a vibration responsive device arranged to provide an electrical voltage at a time coinciding with the passage of an overweighted portion of the rotating cylinder, a reference disc divided into angular segments equal in number to the number of receiving pockets, means associated with said disc for deriving a series of second electrical outputs each corresponding to one of said pockets, said inlet control means comprising an electronic tube circuit including a gas discharge electronic tube and solenoid valve for each pocket, said tube including at least plate, grid and cathode electrodes, said solenoid valves being operative to transfer liquid from said source thereof to an associated pocket, means to apply said first electrical output to said grid and one of said series of second electrical outputs to the plate of each electronic tube whereby said tube is phase-controlled so as to pass an operating amount of current for the solenoid valve in its circuit when said first electrical output has a predetermined phase relationship with said one of said series of second electrical outputs whereby counterbalance liquid is caused to flow through the operated solenoid valve into its associated pocket.

12. Balancing apparatus for a rotatable hollow cylinder for housing discrete articles to be treated, said apparatus comprising a plurality of weight receiving elements arranged to receive counterbalance liquid from a source thereof, said elements being angularly arranged around said cylinder so as to differentially affect the balance thereof when said liquid is selectively applied thereto and a feed ring associated with each element and rotating with the cylinder, said feed ring being substantially channel-shaped so as to have an endless inlet for liquid injected therein, each feed ring communicating with its associated weight receiving element so as to feed the injected liquid thereto.

13. Balancing apparatus as in claim 12, including means to determine the site of unbalance and direct counterbalance liquid to one or more of the feed rings.

14. Balancing apparatus for a rotatable hollow cylinder for housing discrete articles to be treated, said apparatus comprising a plurality of weight receiving elements arranged to receive counterbalance liquid from a source thereof, said elements being angularly arranged around said cylinder so as to differentially affect the balance thereof when said liquid is selectively applied thereto, and a feed ring associated with each element and rotating with the cylinder, said feed ring being substantially channel-shaped so as to have an endless inlet for liquid injected therein, each feed ring communicating with its associated element so as to feed injected liquid thereto, each of the feed rings being connected so as to rotate eccentrically in respect to the cylinder and having discharge outlets which are connected into the respective associated elements, said discharge outlets being disposed at the furthest point of eccentricity.

15. Balancing apparatus for a rotatable hollow

cylinder for housing discrete articles to be treated, said apparatus comprising a plurality of weight receiving pockets arranged to receive counterbalance liquid from a source thereof, said pockets being respectively disposed adjacent spaced peripheral portions of said cylinder so as to differentially affect the balance thereof when said liquid is selectively applied thereto, and a feed ring associated with each pocket and rotating with the cylinder, said feed ring being substantially channel-shaped so as to have an endless inlet for liquid injected therein, each feed ring communicating with its associated pockets so as to feed injected liquid thereto, the feed rings being connected so as to rotate eccentrically in respect to the cylinder and having discharge outlets which are connected into the respective associated pockets, said discharge outlets being disposed at the furthest point of eccentricity, each of said pockets having enclosed rear end walls so as to retain said liquid and having a lower discharge opening whereby liquid fed therein is maintained by centrifugal forces away from said discharge opening and is discharged therethrough in the absence of such centrifugal forces.

16. Balancing apparatus for a rotating hollow cylinder for housing discrete articles to be treated, said apparatus comprising a plurality of weight receiving elements arranged to receive counterbalance liquid from a source thereof, said elements being respectively disposed adjacent spaced portions of said cylinder so as to differentially affect the balance thereof when said liquid is selectively applied thereto, and an annular feed ring associated with each element and rotating with the cylinder, each feed ring being substantially channel-shaped so as to have an endless inlet for liquid injected therein, each feed ring communicating with its associated element so as to feed injected liquid thereto, the feed rings being disposed around the longitudinal axis of the cylinder and having discharge outlets which are connected into the respective associated elements.

17. In an article handling apparatus, including a hollow cylinder rotatable in a stationary shell, balancing means therefor, said balancing means comprising a spaced series of peripherally formed pockets on said cylinder arranged to receive liquid counterbalance material from a source external of said shell, a plurality of feed rings within said shell and communicating with each one of said pockets so as to feed said liquid thereto, each of said feed rings having an annular opening and being channel-shaped in cross-section and having a discharge outlet for feeding liquid to its associated pocket and injection means for directing said liquid into selected feed rings whereby said liquid may be transmitted to selected pockets.

18. Apparatus as in claim 17, including means to determine the site of unbalance in the rotating cylinder and to control the action of the injection means.

19. In an article handling apparatus including a hollow cylinder rotatable in a stationary shell, balancing means therefor, said balancing means comprising a spaced series of peripherally formed pockets on said cylinder arranged to receive liquid counterbalance material from a source external of said shell, a plurality of feed rings within said shell and communicating with each one of said pockets so as to feed said liquid thereto, each of said feed rings having an annular opening and being channel-shaped in cross-section and having a discharge outlet communicating

with its associated pocket, each of said feed rings being eccentrically connected relative to the cylinder so as to rotate eccentrically relative to the axis thereof, said discharge outlet being formed at the furthest point of eccentricity so as to direct liquid thereto through centrifugal action, and injection means travelling from outside of said stationary shell to said feed rings for directing such liquid into selected feed rings whereby such fluid may be transmitted to selected pockets.

20. Balancing apparatus for a rotatable horizontal hollow cylinder comprising a plurality of weight receiving pockets arranged to receive counterbalance liquid from a source thereof, said pockets being respectively disposed adjacent spaced peripheral portions of said cylinder so as to differentially affect the balance thereof when said liquid is selectively applied thereto, said pockets being elongated and extending parallel to the longitudinal axis of the cylinder, front walls formed on one end of each pocket for retaining applied liquid during rotation of the cylinder and pursuant to the generation of centrifugal forces, each of said front end walls being cut away at their lower portions which are in the direction of the cylinder longitudinal axis whereby in the absence of centrifugal forces, liquid will discharge from said pockets through said cut away portion.

21. Balancing apparatus for a rotatable horizontal hollow cylinder comprising a plurality of weight receiving pockets arranged to receive counterbalance liquid from a source thereof, said pockets being respectively disposed adjacent spaced peripheral portions of said cylinder so as to differentially affect the balance thereof when said liquid is selectively applied thereto, said pockets being elongated and extending parallel to the longitudinal axis of the cylinder, front walls formed on one end of each pocket for retaining applied liquid during rotation of the cylinder and pursuant to the generation of centrifugal forces, each of said front end walls being cut away at their lower portions which are in the direction of the cylinder longitudinal axis whereby in the absence of centrifugal forces, liquid will discharge from said pockets through said cut away portion, and a plurality of feed rings eccentrically rotating with and in respect to the cylinder and communicating with respective pockets, said feed rings being channel-shaped and having open annular floors whereby liquid injected at said floors is received in the channel and concentrated at the most eccentric portion of the feed ring, said most eccentric portion being formed with a discharge opening, and a pipe between said discharge opening and the pocket associated with the feed ring.

22. In a balancing apparatus, including a rotatable, hollow cylinder, balancing means therefor, said balancing means comprising a spaced series of peripherally disposed pockets on said cylinder extending parallel to the longitudinal axis thereof and arranged to receive liquid counterbalance material from a source of such liquid, and to maintain the liquid therein by centrifugal force during rotation of the cylinder, a plurality of feed rings each connected to the entrance end of one of said pockets so as to feed said liquid thereto, each of said feed rings having an annular opening and being channel-shaped in cross-section and having a discharge outlet communicating with its connected pockets and injection means for directing said liquid into selected feed rings whereby said liquid may be transmitted to

selected pockets, said pockets having enclosed ends remote from the entrance thereto and having inwardly disposed openings at their entrance ends whereby said liquid may be discharged therefrom at the end of a cleaning operation through gravitational action.

23. Balancing apparatus for a rotatable hollow cylinder for housing discrete articles to be treated, said apparatus comprising a plurality of weight receiving pockets arranged to receive 10 counterbalance liquid from a source thereof, said pockets being respectively disposed adjacent spaced peripheral portions of said cylinder so as to differentially affect the balance thereof when said liquid is selectively applied thereto, solenoid valves for applying said liquid to respective and selected pockets, a vibration responsive device arranged to produce a first electrical voltage at a time substantially coinciding with the passage of an overweighted portion of said cylinder, a reference multiple switch rotating with the cylinder for successively producing a series of electrical voltages each corresponding in time to the angular position of a particular pocket, a control circuit corresponding to the coinciding application of said first electrical voltage and one of said series of voltages for operating at least one valve, a feed ring connected to each pocket and rotating eccentrically with and in respect to the cylinder, said feed ring being channel-shaped so as to have an endless inlet for said liquid, each feed ring being formed with a discharge outlet at its furthest point of eccentricity and communicating with its associated pocket, and a stationary jet connected to each solenoid valve and operative to deliver liquid to its associated feed ring when the valve is operated.

24. Balancing apparatus for a rotatable hollow cylinder for housing discrete articles to be treated, said apparatus comprising a plurality of weight receiving pockets arranged to receive counterbalance liquid from a source thereof, said pockets being respectively disposed adjacent spaced peripheral portions of said cylinder so as to differentially affect the balance thereof when said liquid is selectively applied thereto, and a feed ring associated with each pocket and rotating with the cylinder, said feed ring being substantially channel-shaped so as to have an endless inlet for liquid injected therein, each feed ring communicating with its associated pockets so as to feed injected liquid thereto, the feed rings being connected so as to rotate eccentrically in respect to the cylinder and having discharge outlets which are connected into the respective associated pockets, said discharge outlets being disposed at the furthest point of eccentricity, each feed ring being of greater depth at said furthest point of eccentricity than along any other point thereof.

25. In a balancing apparatus, including a rotatable, hollow cylinder, balancing means therefor, said balancing means comprising a spaced series of peripherally formed pockets on said cylinder extending parallel to the longitudinal axis thereof and arranged to receive liquid counterbalance material from a source of such liquid, and to maintain the liquid therein by centrifugal force during rotation of the cylinder, a plurality of feed rings each connected to the entrance end of one of said pockets so as to feed said liquid thereto, each of said feed rings having an annular opening and being channel-shaped in cross-section and having a discharge outlet communicating with its connected pocket and in-

jection means for directing said liquid into selected feed rings whereby said liquid may be transmitted to selected pockets, said pockets having enclosed ends spaced from the entrance thereto and having inwardly disposed openings at their entrance ends whereby said liquid may be discharged therefrom at the end of an operation through gravitational action, an end chamber for and communicating with each pocket, the total number of chambers occupying substantially 360 degrees of the circumference of the cylinder, each chamber occupying equal areas thereabout, and a conduit for said liquid connected to each feed ring so as to feed liquid to its associated pocket and end chamber.

26. In an apparatus for housing discrete articles to be treated including a hollow cylinder rotatable in a stationary shell, balancing means therefor, said balancing means comprising a 20 spaced series of weight receiving elements on said cylinder arranged to receive liquid counterbalance material from a source external of said shell, a plurality of feed rings each communicating with one of said elements so as to feed said liquid thereto, each of said feed rings having an endless channel for receiving liquid injected therein, and a feed jet for each ring, each feed jet having a discharge nozzle which is directed so that injected liquid flows upwardly into its 30 associated feed ring.

27. In an apparatus for housing discrete articles to be treated, including a hollow cylinder rotatable in a stationary shell, balancing means therefor, said balancing means comprising an angularly spaced series of weight receiving elements on said cylinder arranged to receive liquid counterbalance material, a plurality of feed rings rotatable with the cylinder and each communicating with one of said elements so as to feed 40 injected liquid thereto, and means employing centrifugal forces for both concentrating injected liquid at a discharge point of said feed ring and for directing the flow of such liquid toward the weight receiving element associated with said feed ring.

28. An apparatus as in claim 27, including means operative during rotation of the cylinder in a condition of unbalance, to signal the site of unbalance and direct the counterbalance material to at least one of the feed rings.

29. Balancing apparatus for a rotatable hollow cylinder comprising a plurality of weight receiving pockets arranged to receive counterbalance liquid from a source thereof, said weight receiving pockets being respectively disposed adjacent spaced peripheral portions of said cylinder so as to differentially affect the balance thereof when said liquid is selectively applied thereto, inlet control means for each of said pockets for selectively applying such liquid thereto, a source of voltage including a circuit therefor, a first switch normally maintained in circuit opening position and disposed adjacent to the rotating cylinder 55 whereby eccentric rotation of the cylinder pursuant to a condition of unbalance closes said switch, a control circuit for each of said inlet control means, said control circuit including said source of voltage circuit, a reference multiple switch rotating with the cylinder and included in said control circuit, said multiple switch operative to successively close and open as each pocket arrives at and passes a predetermined point in its rotating travel whereby the coincident closing of said first switch and one closing action

of said multiple switch are required to operate any one of said inlet control means.

30. Balancing apparatus according to claim 29 and wherein said first switch is spring-biased to said circuit opening position so that eccentric rotation of the cylinder closes the switch against the spring action thereof, said multiple switch comprising a distributor disc having segments thereon respectively connected into each of said control circuits, a commutator arm rotating with said cylinder and successively passing over said segments, said source of voltage being connected to said commutator arm whereby each of said control circuits is successively connected to said source of voltage through said first switch depending upon the position thereof.

31. Balancing apparatus for a rotatable hollow cylinder comprising a plurality of weight receiving elements arranged to house varying amounts of weight counterbalance material, drive means for rotating said cylinder, said weight receiving elements being respectively disposed adjacent spaced peripheral portions of said cylinder so as to differentially affect the balance thereof pursuant to the varying amounts of said material housed therein, inlet control means for selectively varying the amounts of said material housed in said receiving elements, a vibration responsive device arranged to provide an electrical voltage pursuant to the passage of an over-weighted portion of the rotating cylinder, reference means operative by the rotation of the cylinder for registering the momentary angular disposition of each spaced peripheral portion of the cylinder, said inlet control means being controlled jointly by said vibration responsive device and said reference means so as to vary the amounts of said material in one or more of said weight receiving elements depending upon the angular position of said over-weighted portion, and means to interrupt operation of said drive means during periods when said inlet control means is operating to vary the amounts of material housed in one or more of said receiving elements.

32. Balancing apparatus for a rotatable hollow cylinder comprising a plurality of weight receiving elements arranged to house varying amounts of weight counterbalance material, a motor for rotating said cylinder, said weight receiving elements being respectively disposed adjacent spaced peripheral portions of said cylinder so as to differentially affect the balance thereof pursuant to the varying amounts of said material housed therein, inlet control means for selectively varying the amounts of said material housed in said receiving elements, a vibration responsive device arranged to provide an electrical voltage pursuant to the passage of an over-weighted portion of the rotating cylinder, reference means operative by the rotation of the cylinder for registering the momentary angular disposition of each spaced peripheral portion of the cylinder, said inlet control means being controlled jointly by said vibration responsive device and said reference means so as to vary the amounts of said material in one or more of said weight receiving elements depending upon the angular position of said over-weighted portion, said apparatus including an electrical circuit to operate said inlet control means, a time delay relay operated through said electrical circuit so as to be energized when the amount of material in any receiving element is being varied by said valve means, said time delay relay being operative to open 75

the motor electrical circuit so as to interrupt motor operation when said inlet control means operates continuously for more than a predetermined period of time.

33. Balancing apparatus for a rotatable hollow cylinder comprising a plurality of weight receiving elements arranged to house varying amounts of weight counterbalance material, a motor for rotating said cylinder, said weight receiving elements being respectively disposed adjacent spaced peripheral portions of said cylinder so as to differentially affect the balance thereof pursuant to the varying amounts of said material housed therein, valve means for selectively varying the amounts of said material housed in said receiving elements, a vibration responsive device arranged to provide an electrical voltage pursuant to the passage of an over-weighted portion of the rotating cylinder, reference means operative by the rotation of the cylinder for registering the momentary angular disposition of each spaced peripheral portion of the cylinder, said valve means being controlled jointly by said vibration responsive device and said reference means so as to vary the amounts of said material in one or more of said weight receiving elements depending upon the angular position of said over-weighted portion, said valve means including a valve and an operating relay therefor for each weight receiving element, an electrical circuit controlling each said operating relay, a time delay relay including a circuit therefor which is closed upon the operation of any valve, said time delay relay being operative to open the motor electrical circuit so as to interrupt motor operation upon the operation of any valve for more than a predetermined period of time and so as to re-institute motor operation upon cessation of valve operation as the balancing of the cylinder progresses.

34. Balancing apparatus according to claim 33 and including a manually operated normally closed stop switch in the motor electrical circuit, opening of said stop switch stopping said motor unless manually closed again, a switch in the electrical circuit of said time delay relay and being normally closed during the operation of the apparatus, a further relay for maintaining said switch in circuit closing position during interruption of motor operation, said last named relay being operated when operation of the motor is initiated.

35. Balancing apparatus for a rotatable hollow cylinder for housing discrete articles to be treated, said apparatus comprising a plurality of weight receiving pockets arranged to receive counterbalance liquid from a source thereof, a feed valve including an operating relay therefor for each pocket, said pockets being respectively disposed adjacent spaced peripheral portions of said cylinder so as to differentially affect the balance thereof when said liquid is selectively applied thereto, a motor for rotating said cylinder including an operating electrical circuit therefor, a vibration responsive device arranged to produce a first electrical voltage at a time substantially coinciding with the passage of an over-weighted portion of said cylinder whereby said first voltage is repeatedly produced during unbalanced rotation of the cylinder and varies in phase depending upon the site of unbalance, a reference multiple switch rotating with the cylinder for successively producing a series of electrical voltages of constant phase each corresponding to the position of a particular pocket, a control circuit re-

sponding to the coinciding application of said first electrical voltage and one of said series of voltages for operating at least one feed valve relay so as to inject said liquid through the feed valve and into its associated pocket, said control circuit being continuously operable during rotation of said cylinder so as to vary the valve relay operation depending upon a further coincidence between said first electrical voltage as its phase may vary during changes of unbalance sites and one of said series of constant phase voltages, a time delay relay operated by said control circuit so as to be energized together with the energization of any feed valve operating relay, an armature controlled by said time delay relay so as to maintain a closed electrical circuit for said motor, said time delay relay operating, after a predetermined period of energization to so actuate its armature as to open the motor electrical circuit.

36. Balancing apparatus for a rotatable hollow cylinder of an article handling machine, including a driving shaft at one end thereof, said apparatus comprising a plurality of weight receiving elements arranged to house varying amounts of weight counterbalance material, said weight receiving elements being respectively disposed adjacent spaced peripheral portions of said cylinder so as to differentially affect the balance thereof pursuant to the varying amounts of said material housed therein, inlet control means including an electrical circuit for selectively varying the amounts of said material housed in said receiving elements, a vibration responsive device arranged to provide an electrical voltage pursuant to the passage of an overweighted portion of the rotating cylinder, said vibration responsive device comprising a pair of members operative to generate an electrical signal upon relative movement, one of said members being connected adjacent one point of said cylinder and shaft and means to transfer vibrations from a second, longitudinally spaced point of said cylinder and shaft to said other member whereby the respective members are subjected to varying vibration forces during rotation of the unbalanced cylinder, and reference means continuously operative during the rotation of the cylinder for electrically registering the momentary angular disposition of each weight receiving element, said inlet control means being controlled jointly by said vibration responsive device, electrical voltage and the electrical action of said reference means so as to vary the amounts of said material in one or more of said weight receiving elements depending upon the site of said overweighted portion.

37. Balancing means for a rotatable hollow cylinder for housing articles to be treated, said balancing means comprising a control system for applying and receiving counterbalance weights at selected peripheral areas of said cylinder, and an electrical pick-up in said control system for detecting the presence of unbalance during cylinder rotation, said pick-up comprising a body and an arm which generates an electrical signal when moved relative to said body, said body being mounted so as to partake of the vibrations of one point along the cylinder longitudinal axis and the pick-up arm being disposed so as to partake of the vibrations of another point along said longitudinal axis.

38. Balancing means for a rotatable hollow cylinder for housing articles to be treated, said cylinder being rotated by a shaft at one end thereof and a motor driving said shaft whereby said cylinder represents an overhanging weight on

said shaft, said balancing means comprising a control system for applying and receiving counterbalance weights at selected peripheral areas of said cylinder, and an electrical pick-up in said control system for detecting the presence of unbalance during cylinder rotations, said pick-up comprising a body member and an operating arm which generates an electrical signal when moved relatively to said body member, said body member being mounted adjacent one point of said shaft so as to partake of the vibrations thereof, and an arm mounted adjacent a longitudinally spaced point of said shaft and extending toward said pickup operating arm so as to transfer the vibrations of said spaced point to said operating arm whereby relative movement between said points on said shaft are detected by said pick-up.

39. Balancing apparatus for a rotatable hollow cylinder comprising a plurality of weight receiving elements arranged to house varying amounts of weight counterbalance material, said weight receiving elements being respectively disposed adjacent spaced peripheral portions of said cylinder so as to differentially affect the balance thereof pursuant to the varying amounts of said material housed therein, inlet control means for selectively varying the amounts of said material housed in said receiving elements, a vibration responsive device arranged to provide an electrical voltage pursuant to the passage of an overweighted portion of the rotating cylinder, reference means operative by the rotation of the cylinder for registering the momentary angular disposition of each spaced peripheral portion of the cylinder, said inlet control means being controlled jointly by said vibration responsive device and said reference means so as to vary the amounts of said material in one or more of said weight receiving elements depending upon the angular position of said overweighted portion, and means to automatically discontinue rotation of said cylinder when vibration thereof exceeds a predetermined level.

40. Balancing apparatus for each end of a rotatable, elongated, hollow cylinder, said apparatus comprising a plurality of weight receiving elements arranged to receive weight counterbalance material from a source thereof, said weight receiving elements being respectively disposed adjacent spaced peripheral portions of said cylinder so as to differentially affect the balance thereof when said material is selectively applied thereto, inlet control means for selectively applying said material to said receiving elements, a vibration responsive device arranged to provide an electrical voltage at a time coinciding with the passage of an overweighted portion of the rotating cylinder, reference means operative by the rotation of the cylinder for registering the momentary angular disposition of each weight receiving element, said inlet control means being controlled jointly by said vibration responsive device and said reference means so as to apply said material to one or more of said weight receiving elements which are in a portion of said cylinder substantially opposed to said overweighted portion, said weight receiving elements, inlet control means, and vibration responsive device being duplicated at each end of the cylinder and operating substantially independently of each other.

41. Balancing apparatus according to claim 26 wherein each of said feed rings is formed with a discharge opening therein and including counterbalance material control means for injecting said material into said feed rings, said

discharge openings communicating with the respective weight receiving elements.

42. Balancing apparatus for each end of a rotatable, elongated, hollow cylinder having a trunnion at each end thereof and anti-friction bearings at each trunnion, said apparatus comprising a plurality of weight receiving elements arranged to receive varying quantities of weight counterbalance material, said weight receiving elements being angularly and spacedly arranged around and at both ends of said cylinder so as to differentially affect the cylinder balance at said ends when said material is selectively applied to the elements, a plurality of feed rings for receiving injected fluid and for transmitting said fluid to an associated weight receiving element, said plurality of feed rings being substantially duplicated at each end of the cylinder and being rotatable therewith, said weight receiving elements and feed rings being disposed adjacent said trunnions at each end of the cylinder.

43. Balancing apparatus for each end of a rotatable, elongated, hollow cylinder having end trunnions and anti-friction bearings at each trunnion, said apparatus comprising a plurality of elongated, weight receiving elements arranged parallel to the longitudinal axis of the cylinder and angularly spaced adjacent the periphery of the cylinder, a series of said weight receiving elements being duplicated at each end of the cylinder so that the elements at each end

extend toward each other, each of said elements at one end of the cylinder terminating within a central point of the cylinder so as to be isolated from the other end thereof, and means to selectively apply weight counterbalance material to said receiving elements.
